UNITED STATES PATENT OFFICE.

HARRY L. GARBUTT, OF WILKINSBURG, PENNSYLVANIA, ASSIGNOR TO WESTINGHOUSE ELECTRIC & MANUFACTURING COMPANY, A CORPORATION OF PENNSYLVANIA.

TROLLEY-HANGER.

1,374,561.

Specification of Letters Patent. Patented Apr. 12, 1921.

Application filed January 16, 1917. Serial No. 142,633.

To all whom it may concern:

Be it known that I, HARRY L. GARBUTT, a citizen of the United States, and a resident of Wilkinsburg, in the county of Allegheny and State of Pennsylvania, have invented a new and useful Improvement in Trolley-Hangers, of which the following is a specification.

My invention relates to trolley hangers and it has for one of its objects to provide a trolley-supporting means which will positively insulate the trolley conductor from the supporting cables and will not release the trolley conductor even though the insulating units become broken.

Another object of my invention is to provide an insulator with a shield which will protect the same from wild trolley poles, missiles, and the like.

20 A further object of my invention is to provide an insulated trolley hanger in which the rapidly wearing parts may be readily renewed without in any way releasing the main supporting structure.

25 A further object of my invention is to provide a trolley ear which is pivotally secured to the supporting base and which will align itself with the trolley conductor.

A further object of my invention is to 30 provide a device of the above-indicated character in which a plurality of trolley ears may be assembled in side-by-side relation upon a single insulated supporting structure.

35 A further object of my invention is to provide a trolley ear which will yield slightly under the impact of the trolley wheel and thereby prevent the rapid wearing away of the trolley ear.

40 My invention provides two strain insulators having a cable extending therebetween to which a trolley-supporting ear is secured.

Figure 1 of the accompanying drawing is a top plan view of a trolley-supporting 45 device embodying my invention; Fig. 2 is an end elevational view of the device shown in Fig. 1; and Fig. 3 is a top plan view of a portion of the clamping means shown in Fig. 1.

50 The trolley hanger shown in the drawing comprises a plurality of strain insulators 1 having a cable 2 extending therebetween, upon which a clamping member 3 and a

trolley-supporting ear 4 are mounted. The strain insulators 1 are preferably of an interlocked type in which a supporting cable 5 is looped with the cable 2. The clamping member 3 has a bottom piece 6 that is provided with a corrugated surface having cable-clamping grooves 7, of substantially 60 semi-circular cross-section, which extend diagonally across the member 6 and are adapted to admit the ends of the cable 2 at diametrically opposite points. Oppositely extending shields 8 are provided to 65 protect the insulators 1 from disengaged trolley wheels and the like. A top clamping piece 9 has corrugations and grooves corresponding to those of the member 6 and is secured thereto by clamping bolts 70 10. The trolley ear 4 is secured in place by a single bolt 11, which permits of a pivotal movement of the trolley ear, thus aligning the same with a supported trolley conductor 13.

75 The grooves 7 provide considerable clamping surface for the cable 2 and secure the same solidly in place by having a plurality of corrugations, as set forth. Since the trolley ear 4 is secured in place by a single 80 bolt 11, it will be seen that there will be no necessity of loosening the clamp 3 in order to renew the trolley-supporting member 4, which necessarily wears away rapidly. The cable 2 is of relatively light weight and 85 is slightly flexible, thereby yielding under a sudden impact from a passing trolley wheel upon the trolley ear 4.

Although I have described my invention in a simple and preferred form, it will 90 readily be seen that numerous types of strain insulators and cable-clamping devices may be employed therewith, and I desire, therefore, that only such limitations shall be imposed as are indicated in the appended claims.

I claim as my invention:

1. A trolley hanger comprising a looped cable, a clamp for securing the ends of said cable, insulating supporting means interlinking said cable at each end of the major axis thereof, and a trolley-conductor-supporting means secured to said clamp.

2. A trolley hanger comprising a looped flexible member, a clamp for securing the ends thereof, insulating members inter-

linked by said flexible member, and trolley-conductor-supporting means secured to said clamp.

3. A trolley hanger comprising a looped member, means for securing the ends thereof, insulators interlinked by said looped member and means for securing a trolley conductor to said securing means.

4. A trolley hanger comprising a pair of strain insulators, a cable extending through said insulators, a clamp for securing the ends of said cable having oppositely and outwardly extending arms for protecting said insulators, and wire-supporting means secured to said clamp.

5. The combination with a looped member, of insulators interlinked thereby, and means for securing the ends of the looped member and for supporting a conductor.

20 6. A trolley hanger comprising a plurality of insulators, a cable for connecting said insulators, means for clamping the ends

of said cable together, arms extending outwardly from said clamping means for protecting said insulators, and trolley-conductor-supporting means secured to said clamping means.

7. The combination with a flexible suspension structure comprising metal end and intermediate members disposed in spaced substantially end-to-end relation, of strain insulators comprising blocks of insulating material disposed in the spaces between said metal members and each having a seat portion at each end, one of which seat portions is at substantially right angles to the other, said metal members interlinking said blocks and being disposed in said seat portions, and means for supporting a conductor between said blocks.

In testimony whereof, I have hereunto subscribed my name this 9th day of Jan., 1917.

H. L. GARBUTT.
